UNITED STATES PATENT OFFICE.

STEPHEN A. STAEGE, OF PITTSBURGH, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Application filed May 11, 1925. Serial No. 29,410.

My invention relates to regulator systems and more particularly to rheostats of the rotary contactor type for use in such systems.

5 One object of my invention is to provide an adjustable resistor having a practically infinite number of effective resistance steps.

A further object of my invention is to provide a regulator system of the above-10 indicated character, having rotary contactors adapted to intermittently short-circuit a resistor for varying durations of time to control the effective value thereof.

In practicing my invention, I make use 15 of rotary contactors of the type disclosed in application Serial #530,708, filed by William E. Menzies, for speed regulator systems, on Jan. 30, 1922, and assigned to the Westinghouse Electric & Manufacturing

20 Company.

In my rotary contactor-type rheostat, rotary contactors of the Menzies type are driven by any suitable device at any desired speed and are utilized as an adjustable resistor to effect the control of the speed of 25 a motor or the voltage of a generator or for any purpose for which a rheostat may be employed.

I preferably make use of two or more rotary contactor drums of the Menzies type, 30 connected together by a differential-gear device, the center element or housing of which is rotatable and may be operated by hand or by a small motor, preferably through a 35 worm gear.

The rotary contactor drums comprise 40 conducting and non-conducting sets of segments, and pairs of cooperating drums are connected in series-circuit relation with each other and in shunt-circuit relation to the regulated resistor that is connected in the shunt field circuit of the motor to be controlled.

The angular phase positions of the 45 rotary contactor drums determine the percentage of time that the resistance units are in circuit or short-circuited, thus, determining their effective values. By rotating the housing or middle element of the differential gear device in the one or the other direction, the 50 angle of phase displacement of one drum with respect to the other is varied, thus causing the effective value of the resistance in the circuit to be varied. When there is a zero

phase displacement between the drums, the 55 resistance is not included in circuit at all, whereas, if there is 180° phase displacement, the resistance is then included in circuit all of the time. For intermediate degrees of displacement, the percentage of the time the 60 resistance is in the field-winding circuit of the motor or the generator is proportional to the angle of displacement between the rotary contactors.

In the accompanying drawing, Fig. 1 is 65 a diagrammatic view of the circuits and apparatus employed in one embodiment of my invention;

Fig. 2 is a development of the rotary contactors, showing the relative time periods 70 that the resistor sections are short circuited for different phase positions of the rotary contactors;

Fig. 3 shows an application of my invention 75 to a sectionally driven paper-making machine; and

Fig. 4 shows an arrangement of rotary contactors for a master-control rheostat for sectional paper-machine drives.

Referring to the drawing, a dynamo-electric machine 1 is illustrated as provided with 80 an armature winding 2 and a field winding 3 that are connected to the supply conductors 4 and 5. In series-circuit relation with the field winding 3, a resistor 6 is provided, 85 which may comprise sections 7 and 8. Rotary contactors 11, 12 and 13 are driven by a suitable motor 14 comprising an armature winding 15 and a field winding 16 that are connected by means of conductors 17 and 18 90 to the supply conductors 4 and 5.

The rotary contactor 11 is shown as provided with staggered conducting sections 19 and 21 and staggered non-conducting sections 22 and 23, all adapted to form 95 a smooth cylindrical contacting surface. Likewise, the rotary contactor 12 is shown as provided with conducting sections 24 and 25 and non-conducting sections 26 and 27; and the contactor 13 is provided with similar 100 conducting sections 28 and 29 and non-conducting sections 31 and 32.

The several rotary contactors are respectively provided with brushes 33, 34 and 35, 105 which are of sufficient width to successively engage both of the staggered conducting sections of the corresponding contactors and are connected respectively to the middle

point of the resistor 6 and to the end points of the resistor sections 8 and 7. The rotary contactor 11 is provided also with narrow alined brushes 36 and 37, each of which alternately engages a conducting and a non-conducting segment of the contactor, these brushes being respectively connected to brushes 38 and 39 of the contactor 12. Similar brushes 41 and 42 of the contactor 11 are connected to brushes 43 and 44, respectively of the contactor 14.

The rotary contactor 11 is mounted upon a shaft 45 that is directly driven by the motor 14, and the contactors 12 and 13 are mounted upon a shaft 46 that is driven through a differential mechanism 47 in accordance with the speed of the motor 14. The differential mechanism 47 comprises bevel gear-wheels 48 and 49 that are secured to the shafts 45 and 46 respectively, to engage bevel gear-wheels 51 that are mounted upon housing 52. The gear-wheels 51 and the housing 52 together comprise the middle or planetary element of the differential mechanism. The housing is provided with a worm gear that is operated by means of a worm 53 in accordance with the operation of a shunt-type motor 54. The motor 54 comprises an armature 55 and a field winding 56 that are energized from a suitable source 57, and is controlled by means of a reversing switch 58.

Fig. 2 of the drawing discloses a development of the drum surfaces of the rotary contactors 11, 12 and 13, the several views *a*, *b*, *c*, *d*, *e* and *f* showing different phase relations between the rotary contactors. The shaded strip at the extreme left of each of these views shows the proportionate value of resistance in the field circuit of the motor 1. In the view *a*, the position of the rotary contactors is such that there is a continuous short circuit of the resistor 6. In the view *c*, one of the resistor sections is shown continuously short circuited while the other is open circuited, giving, in effect, a value of resistance equal to one-half that of the resistor 6, in circuit with the field winding. In the view *f*, the entire resistance is in the field winding circuit. The other views show intermediate values of resistance and the position of the rotary contactors corresponding thereto.

The diagrams of connections between the several brushes are indicated below the development of the corresponding rotary contactor drums and show each brush in line with the conducting and non-conducting segments engaged by that brush, and also show the spacing of brushes 36 and 37 from brushes 41 and 42 as equal to one-half the length of the conducting segments 19 and 21.

By a study of the view *a* in Fig. 2, it will be noted that the brushes 33, 34 and 35, continuously engage the conducting seg-

ments of their respective contactor drums 11, 12 and 13. The brushes 36 and 37, and also the brushes 41 and 42, alternately engage the conducting and non-conducting segments 19 and 23, and 21 and 22, respectively, while the brushes 38 and 39 engage conducting and non-conducting segments 24 and 27, and 25 and 26, respectively, and the brushes 43 and 44 of the contactor 13 engage conducting and non-conducting segments 28 and 32, and 29 and 31, respectively.

Assuming that the several brushes are moving upwardly across the development of the drums, as illustrated, it will be seen that the brush 36 passes from the non-conducting segment 23 to the conducting segment 19 at the same time that the brush 38 passes from the non-conducting segment 27 to the conducting segment 24, so that the segments 19 and 24 of the contactors 11 and 12 are connected together, thereby short-circuiting the section 8 of the resistor for a certain period of rotation. As the brushes 36 and 38 pass from the conducting segments 19 and 24, respectively, to the following non-conducting segments 23 and 27, the brushes 37 and 39 will pass from their respective non-conducting segments 22 and 26 to the conducting segments 21 and 25, respectively, of the contactors 11 and 12, thereby closing the circuit between the brushes 33 and 34 through the brushes 37 and 39 at the same instant that the circuit is broken between brushes 36 and 38, thereby giving the effect of a permanent short-circuit between the brushes 33 and 34 for short-circuiting the resistor section 8 throughout the entire rotation of the rotary contactor drum.

Similarly, it will be noted that the drum 13 is displaced, with respect to the drum 12, a distance equal to one half the length of the conducting and non-conducting segments and that the brushes 41 and 42 are similarly displaced with respect to brushes 36 and 37, so that the circuit conditions between the contactor drums 11 and 13 are exactly the same as between the contactor drums 11 and 12. That is to say, in the position shown in the view *a*, the brush 43 will pass from a non-conducting segment 32 to a conducting segment 28, at the same time that the brush 41 passes from a non-conducting segment 23 to the conducting segment 19, so that, during the entire passage of the brush 41 across the conducting segment 19, the brush 43 will be passing across conducting segment 28, thus short-circuiting the resistor section 7. Also, as the brushes 41 and 43 engage the non-conducting segments 23 and 32, respectively, the brushes 42 and 44 will engage the conducting segments 21 and 29 of the contactor drums, thus completing the circuit through the brushes 42 and 44 at the instant that the circuit is broken through the brushes 41 and 132

43, and thus continually short-circuiting the resistor section 7.

With the displacement of the contactor drums illustrated in view *b*, there will be an intermittent short-circuiting of the resistor sections 7 and 8, as the brushes pass over the contactor drums. The duration of the open circuit and the effective value of resistance inserted in the circuit is indicated in the cross-hatched strip at the left of the drum development. In the view *c*, the proportion of time that the resistor sections 7 and 8 are short-circuited is diminished, so that the open and short-circuited durations of time are of equal value, giving an effective value of resistance equal to one-half that of the resistor 8. Similarly, the views *d*, *e* and *f* show the effective value of resistance in circuit, with varying phase positions between the rotary contactor drums 11, 12 and 14, the view *f* corresponding to the extreme opposite position from that illustrated in view *a*, namely, a phase variation of 180° , corresponding to conditions during which no short-circuiting will be produced through the rotary contactors. Consequently, the entire value of the resistor 6 will be effective in the field circuit of the motor.

In Fig. 3 of the drawing, I have illustrated my invention as applied for use with a sectional paper-mill drive, where both generator and motor field-circuit control is desired to control the speed of the paper-making machine. The speed regulator illustrated in this view corresponds to the Menzies type regulator referred to above. A single paper machine roll 61 and a single driving motor 62, are illustrated, although it will be understood that this represents only one section of a sectionally driven machine. The motor 62 drives the roll 61 through shaft 63 and gear-wheels 65 and 66. The motor 62 comprises an armature winding 67 that is connected to a variable-voltage supply circuit 68 and 69 by means of conductors 71 and 72, and is also provided with a field winding 73 that is connected to constant-potential supply conductors 74 and 75 by means of conductors 76 and 77. In circuit with the field winding 73 of the section motor, I provide a resistor 78 comprising sections 79 and 81 and a resistor 82 comprising sections 83 and 84.

The master speed-reference means 85 comprises a motor having an armature winding 86 and a field winding 87, the armature winding being connected by means of conductors 88 and 89 to the variable-voltage supply conductors 68 and 69, and the field winding 87 being connected by means of conductors 91 and 92 to the constant-potential supply conductors 74 and 75. In circuit with the field winding 87, a resistor 93 is provided, comprising sections 94 and 95.

A number of rotary contactors 96 of the Menzies type are driven by the master motor 85, one of which is shown as connected to the rotary contactors 97 and 98, which are driven in accordance with the operation of the section roll 61, by means of shaft 99, co-operating cone pulleys 101 and 102, gearing mechanism 103 and shaft 104. The remaining contactors that are driven by the master speed-reference motor 85, may be connected to control the speed of the other section driving motors, as will be readily understood.

It is desirable to vary the speed of the entire group of motors driving the paper-making machine in such manner that they remain in speed harmony, although operating at a different speed. This result may be effected by varying the voltage supplied to the armatures of the several section motors that are connected to the supply conductors 68 and 69.

It is, however, desirable in some cases to use a direct rheostat control for varying the speed of the motors. My invention lends itself readily to the use of a number of rheostats, one connected in the field circuit of each of the section motors, and all of them being controlled simultaneously. For example, a motor 105 drives a shaft 106, upon which are mounted a number of rotary contactors 107, 108 and 109, of the type described above and, through a differential mechanism 111, a shaft 112 drives a similar set of contactors 113 to 118. In the differential device 111, a gear-wheel 119 is secured to the shaft 106 and a gear-wheel 121 is secured to the shaft 112. Each of these end gear-wheels meshes with the gear-wheels 122 comprising the middle element of the differential device, which element is driven through a worm 123 by a motor 124, as described in the system of Fig. 1.

It will be noted that the rotary contactors 107, 113 and 114 are connected to control the effective value of the resistor 93 and that the rotary contactors 109, 117 and 118 are connected to control the effective value of the resistor 82. Similarly, any number of resistors in the field circuits of a like number of motors may be controlled at the same time.

In Fig. 4, I have illustrated one layout of the rotary contactor drums and the means for operating them. The several sets of drums 125, 126, 127 and 128 may be operated by a single motor 129 by means of gear-wheels 131, 132 and 133, and differential mechanisms 134 and 135. The respective housings 136 and 137 of the differential mechanisms may be jointly operated by means of a worm 138 and a worm gear 139 that is engaged by a worm upon the shaft 141, which is driven by a motor 142 for effecting changes in the relative positions

of the contactor drums. The layout of the rotary contactor drums illustrated in Fig. 4 does away with the necessity of having extremely long shafts upon which to mount the several rotary contactor drums.

While I have illustrated my rotary-type rheostat as operating upon two sections of a resistor element, it is obvious that, by the use of only two contactor drums, the entire resistance might be controlled in the same manner as the individual sections of the rheostat have been described as being controlled, and also that by increasing the number of rotary contactors used, any number of sections of the resistor may be controlled. The pilot motor controlling the phase displacement between the rotary contactor drums may be operated by a push-button control or it may be operated as the pilot 20 motor or rheostat motor of any regulator system where a motor-operated rheostat is desirable.

Many modifications in the apparatus and circuits employed and in the location of parts may be made within the spirit of my invention, and I do not wish to be limited other than by the scope of the appended claims.

I claim as my invention:

1. In a regulator, a resistor element, a plurality of rotary contactors connected to said resistor element and mechanically interconnected to operate in a predetermined phase relation, and means for varying the phase relation between certain of said rotary contactors to vary the effective value of said resistor element.

2. In a regulator, a resistor element, a plurality of rotary contactors connected to said resistor element and mechanically interconnected to operate in predetermined relative positions, connecting means between said rotary contactors, and means for varying the relative positions of said rotary contactors to vary the effective value of said resistor element.

3. In a regulator, a resistor element, a plurality of rotary contactors connected to said resistor element and mechanically interconnected to operate in predetermined relative positions, said rotary contactors being adapted to intermittently short-circuit said resistor element, and means for varying the relative position of said rotary con-

tactors to vary the effective value of said 55 resistor element.

4. In a regulator, a resistor element, means for determining the effective value of said resistor element comprising cooperating rotary contactors mechanically interconnected to operate in predetermined relative positions, and means for varying the relative position of said rotary contactors to vary the effective value of said resistor element.

5. In a regulator, a resistor element, a plurality of rotary contactors connected to said resistor element, means for actuating said rotary contactors in a fixed speed relation, and means for varying the phase relation between said rotary contactors.

6. In a regulator, a resistor element, rotary contactors connected to said resistor element, means for actuating said contactors in a fixed speed relation, means for connecting said contactors to intermittently short-circuit said resistor element, and means for varying the phase relation between said rotary contactors to vary the duration of said short-circuits.

7. In a regulator, a resistor element, a plurality of rotary contactors connected to said resistor element and actuated to have a fixed speed relation, and means for varying the relative position of said rotary contactors to vary the effective value of said resistor element.

8. In a regulator, a sectional resistor element, means for determining the effective value of said resistor element comprising cooperating rotary contactors connected in series circuit relation with each other for completing circuits in shunt relation to said resistor sections for intermittently short-circuiting said sections, and means for varying the duration of said short-circuits.

9. In a rotary rheostat, a sectional resistor element, rotary contactor means adapted to intermittently short-circuit the respective sections of said resistor element, and means for varying the setting of said rotary contactor means to vary the effective value of said resistor element.

In testimony whereof, I have hereunto subscribed my name this 29th day of April, 1925.

STEPHEN A. STAEGE.
